APPLIQUE PROCESS

Lynde De Forest Hokerk, Utica, N. Y.

Application February 28, 1931. Serial No. 519,100

2 Claims. (Cl. 41—34)

The present invention relates to applique work and the method of producing the same, and particularly to a method of permanently affixing appliques cut out from various materials such as 5 cloth, paper, felt, artificial leather, oilcloth, leather, wood, etc. to a base material such as a textile fabric, oilcloth, leather, artificial leather, metal, glass, paper, wood, or the like.

The present invention has for its object to 10 provide a method of manufacturing appliqued material and articles which is rapid and inexpensive and which is applicable to a great variety of materials.

A further object is to produce appliqued 15 materials and articles which may be washed or immersed in water without injury to the appliques or to the material to which the appliques are affixed, and particularly to produce appliqued fabric and appliqued fabric articles which may 20 be laundered without loosening the applique and without causing distortion of the fabric or the appliques due to uneven shrinkage of the base material and applique material or material such as 25 thread with which many appliques are applied.

A further object is to provide a method of producing applique work in which the appliques are provided with a backing of vulcanizable material and are permanently and securely affixed to the 30 base material by the simultaneous application of heat and pressure.

A further object is to provide a method of manufacturing applique material with a permanent backing in the form of a sheet or film of vulcanizable material so that appliques cut from said 35 material may be applied directly to the base material and be affixed thereto by the application of heat and pressure.

A further object is to provide a method of affixing 40 appliques to a base material without the use of liquid pastes or cement, so that soiling of the base material or the applique material in the process of affixing the applique to the base material is avoided.

With the above and other objects in view the 45 invention may be said to comprise applique work and method of producing the same as illustrated in the accompanying drawing hereinafter described and particularly set forth in the appended 50 claims, together with such variations and modifications thereof as will be apparent to one skilled in the art to which the invention appertains.

Reference should be had to the accompanying drawing forming a part of this specification, in 55 which:

Fig. 1 is a plan view showing a piece of applique work embodying the invention.

Fig. 2 is a fragmentary section taken on the line indicated at 2—2 in Fig. 1;

Fig. 3 is a diagrammatic view illustrating the 60 method of applying a backing composed of a sheet of vulcanizable material to a sheet of applique material, and also showing how the applique material with the backing thereon is wound on a 65 reel for drying;

Fig. 4 is a diagrammatic view illustrating the 70 method of affixing the appliques to the base material.

In Fig. 1 of the drawing there is shown a piece 75 of applique work which consists of a piece of base material 1 which may be a textile fabric and which has affixed to the surface thereof ornamental figures in the form of appliques 2.

The method of the present invention consists 80 in preparing the applique material, blocking out 73 the individual appliques from said material and affixing the appliques to the base material.

The first operation consists in cementing to the 85 applique material, a backing composed of a thin sheet of vulcanizable material and allowing the 80 cement to dry or set to permanently secure the backing to the applique material. The individual 90 appliques to be applied to the base material are then cut or blocked out from the sheet of applique material. The affixing of the appliques to the 95 surface of the base material is effected by placing the appliques in the proper position on the base material and then applying heat and pressure simultaneously to the applique and base material to vulcanize the applique backing to the base 100 material.

As shown in Fig. 3 of the drawing the applique material in the form of a sheet 3 has applied thereto a backing 4 composed of a thin sheet of vulcanizable material, preferably gutta percha. 95 The sheet of vulcanizable material is of a width to cover the entire surface of the sheet of applique material to which it is applied and is securely cemented thereto.

In applying the sheet of vulcanizable material 100 to the sheet of applique material one surface of the vulcanizable material is treated with a light rubber cement which contains a sufficient excess of solvent to partially dissolve the vulcanizable material on the face to which the cement is 105 applied, producing a very thick, sticky cement mixture on the face of the sheet. The opposite or untreated side of the vulcanizable material retains the general characteristics of dry rubber sheeting since not enough cement is sup- 110

plied to penetrate through the sheeting. A short time after being thus treated the surface of the cemented sheet becomes very tacky and sticky and, after the interval of time necessary to provide the proper degree of tackiness, the sheet of vulcanizable material is brought into contact with the sheet of appliquéd material throughout the extent thereof. As illustrated in Fig. 3, the sheet 3 of appliquéd material and the sheet 4 of vulcanizable material may be delivered from rolls 5 and 6, respectively, to pressure rolls 7, the sheet 4 passing over an intermediate idler roll 8. A suitable solvent, preferably a light rubber cement may be applied to the sheet 4 by a suitable coating device 9 positioned at a sufficient distance from the pressure rolls 7 to give the solvent the necessary time to act on the vulcanizable material before it is brought into contact with the appliquéd material.

While the sheet of vulcanizable material is drying on the fabric or other appliquéd material, it has a tendency to shrink, shrivel and finally separate from the fabric or other material, this tendency being probably due to the action of the solvent vapors continuing to penetrate the sheet of vulcanizable material during the drying process and to the natural tendency of the vulcanizable material to shrink as the volatile substances in the cement are dissipated. It is, therefore, necessary to positively hold the backing sheet against shrinking during the drying operation, and this is preferably accomplished by winding the appliquéd material as it is delivered from the rolls 7 on a reel 10 with the backing sheet on the outside and with sufficient tension to positively hold the backing sheet under tension and compressed against the surface of the appliquéd material while it is drying.

After the appliquéd material is thoroughly dried it has a perfectly cemented, dry, flexible backing of vulcanizable material and appliqués of the desired configuration can be cut from the sheet stock by means of dies or the like.

After the appliqués have been cut from the sheet of appliquéd material they may be applied to the surface of a base material by simply placing them in the proper position on the surface of the material and simultaneously applying heat and pressure to vulcanize the backing to the base material. The thickness of the sheeting of gutta percha or other vulcanizable material will vary somewhat depending upon the character of the appliquéd work but is preferably quite thin, sheets of a thickness of from ".0025" to ".0085" having been found to be suitable for most commercial applications.

The rubber cement employed may be of varying concentrations but generally a cement containing about two pounds of rubber per gallon is preferred. Benzol and toluol have been found to be satisfactory solvents and quick acting accelerators kicking off at low temperatures may be used in the compound but are not essential.

The temperatures used in affixing the appliquéd to the base material vary with different appliquéd and base materials depending on the thickness, scorching temperature and time required for the heat to penetrate the materials, the temperatures to which the materials are subjected varying from 250° F. to 500° F.

As shown in Fig. 4 the appliqués may be

placed upon a sheet of base material on a table 11 and vulcanized to the base material by pressing the base material with the appliqués thereon between suitable pairs of opposed steam heated platens 12.

The backing of gutta percha or other vulcanizable material is highly advantageous where the appliquéd material is a fabric such as felt since it positively holds the fabric against stretching before and after the cutting operation, and the appliqués cut from the appliquéd material are clearer and more distinct in outline than they would be if cut from untreated fabric.

Appliquéd fabrics produced by the present invention can be laundered very successfully and satisfactorily since the vulcanized film is insoluble in water and has sufficient elasticity to compensate for shrinkage of the material due to the laundering so that neither the appliquéd nor the backing fabric is distorted due to the laundering operation.

It will be apparent that the present invention provides an extremely simple and rapid method of producing appliquéd work particularly appliquéd fabric or fabric articles since the slow and laborious operation of attaching the appliqués to the fabric base by cementing or stitching the individual appliqués is eliminated.

Furthermore, the present invention produces very neat and attractive applique work by reason of the fact that the designs are clear and distinct and there is no staining of either the applique or the base to which it is applied.

It will also be apparent that the most complicated of designs may be applied to a backing fabric or material with very little more labor than that required for the simplest of designs.

Furthermore, it is to be understood that the particular product shown and described, and the particular procedure set forth, are presented for purposes of explanation and illustration and that various modifications of said product and procedure can be made without departing from my invention as defined in the appended claims.

I claim:

1. The herein described method of forming appliqués which consists in applying a volatile solvent to one face of a sheet of vulcanizable material to make said face tacky, affixing said sheet to a sheet of applique material by pressing the tacky face thereof against the applique material to cause the sheet of vulcanizable material to adhere to the applique material and form a backing therefor, winding said applique material into a roll with the vulcanizable backing on the outside so that the vulcanizable backing sheet is held under tension while drying, and cutting appliques from said applique material.

2. The herein described method of forming applique material which consists in coating one face of a sheet of vulcanizable material with a volatile solvent to make said face tacky, pressing the tacky face of said material against a sheet of applique material to cause the vulcanizable material to adhere to the applique material and form a backing therefor, and forming said material to curved shape with the vulcanizable backing providing the convex surface thereof so that the vulcanizable backing sheet is held under tension while drying.

LYNDE DE FOREST HOKERK.
